CIRCUIT INTERRUPTER.

Application filed August 22, 1922. Serial No. 583,563.

Our invention relates to circuit interrupters and particularly to protective devices therefor for controlling the arcs that may be formed across the relatively movable contact members.

In the operation of circuit breakers that are provided with main contact members and arcing tips, there is sometimes a tendency for the current to concentrate at, and 10 to form arcs across, the main contact members at their points of final engagement. This action occurs because of the relatively high inductance of the arcing tip path and results in erosion of the surfaces of the main 15 contact members.

In the usual design of arcing tip and main contact circuits, the materials used in, and the proportions of the former are such that the arcing tip circuit has an inherent- 20 ly high inductance compared to that of the circuit through the main contact members. This higher inductance sometimes results in a perceptible delay in the transfer of current flow from the main contact members to the arcing tip circuit.

Our invention has for its object the provision of means for facilitating the transfer of an arc from the main contact members to the arcing tips.

As shown in the accompanying drawing, 25 Figure 1 is a view showing the manner in which our invention may be applied to a circuit breaker, and

Figs. 2 and 3 show embodiments of our 30 invention.

Only so much of a circuit breaker is shown as is necessary to explain our invention. A lifting rod 4 carries the usual bridging member 5 that is provided with a brush 6 and carries movable arcing tips 7 and 8 that are biased upwardly into engagement with stationary arcing tips 9 and 10, respectively, in the manner well known to those skilled in devices of this character.

The brush 6 is provided with loops 11, of magnetic material, and co-operates with stationary contact members 12. Upon the separation of the brush 6 from the stationary contact members 12, the establishment 45 of current flow across the arcing tips is delayed and arcs tend to form across those points of the main contact members last in engagement. By providing loops 11 of

steel, or other magnetic material, the inductance of the brush member is increased to 55 a value slightly greater than that of the arcing-tip circuit, thereby rendering that accelerating circuit less resistant to current flow and the diversion of current from the brush 6 to the arcing tip circuit, thus materially reducing the tendency to maintain current flow through the main contacts when separating the bridging member 6 from the contact members 12.

The operation of the device of Fig. 2 is 65 substantially the same as that of Fig. 1, a brush 12 serving as the stationary contact member, and a bridging member 6^a serving as the movable contact member. An inductance member 11^a functions in the same 70 manner as the member 11 of Fig. 1.

Fig. 3 shows still another modification of our invention. In this form, the stationary contact member 14 is provided with an arcing tip 15 which co-operates with a movable arcing tip 16 that is yieldingly supported upon the bridging member 17 which carries the brush member 18, that co-operates 75 with the stationary contact member 14.

Instead of providing a loop about the bridging member 18 for increasing the inductance thereof, we intersperse strips of steel, 19, 20, 21, 22 and 23, between the copper laminations of the bridging member 18. These steel inserts not only produce a reactive effect, but cause a more uniform 80 distribution of the current throughout the brush.

In conductors of this character, a rapidly changing current tends to concentrate at 90 their perimeter. By making the inserts 22 and 23 longer than the intermediate inserts 19, 20 and 21, the inductance at the perimeter is greater than at the middle, so that a substantially uniform distribution of 95 the current throughout the body of the brush 18 is effected. Therefore, the tendency towards the formation of arcs across the main contact members is reduced, both by reason of the uniform distribution of 100 current throughout the contact member and by the inductance secured through the use of the magnetizable inserts 19, 20, 21, 22 and 23.

The loops 11 and 11^a, also tend to effect 105 a more uniform distribution of the current

in the brush members, particularly if placed close to the ends of the contact members as shown in Fig. 2.

Various changes in detail and general arrangement may be made without departing from the spirit and scope of the invention, as defined in the accompanying claims.

We claim as our invention:

1. The combination with two relatively movable main contact members and a pair of relatively movable auxiliary contact members, of means for increasing the inductance of one of the main contact members.
2. The combination with two relatively movable main contact members and a pair of relatively movable auxiliary contact members, of means for effecting a substantially uniform distribution of current in one of the main contact members.
3. The combination with two auxiliary conducting members, of two relatively movable main conducting members, one of which is provided with means for increasing the inductance of the circuit therethrough.
4. The combination with a pair of arcing tips, of two relatively movable main contact members, one of which is provided with a loop of magnetic material.
5. The combination with a pair of arcing tips, of two relatively movable main contact members, one of which is provided with a magnetizable portion for increasing the inductance thereof.
6. The combination with co-operating arcing tips, of two relatively movable contact members, and inductive means carried by one of said contact members for facilitating the transfer of current flow from the said contact members to the arcing tips.
7. The combination with co-operating arcing tips, of two relatively movable contact members, and an inductive member associated with one of the said contact members

for facilitating the transfer of current flow from the said contact members to the arcing tips.

8. The combination with co-operating arcing tips, of two relatively movable contact members, and means for increasing the inductance of one of the said contact members, to facilitate the transfer of current flow from the said contact members to the arcing tips.

9. The combination with an auxiliary conducting circuit, of a main circuit having a pair of conducting terminals, one of which is provided with means for increasing the inductance thereof.

10. A circuit-interrupting device comprising means for establishing a main current-carrying path of relatively low impedance, means for providing an auxiliary current path of relatively high impedance, the current from the main path being diverted to said auxiliary path upon opening said interrupter, and means for increasing the impedance of the main path to the development of a current therethrough to a value comparable to the impedance of said auxiliary path.

11. A circuit-interrupting device comprising means for establishing a main current-carrying path of relatively low impedance, means for providing an auxiliary current path of relatively high impedance, the current from the main path being diverted to said auxiliary path upon opening said interrupter, and means for increasing the impedance of the main path to facilitate the diversion of current from the said main path to the said auxiliary path.

In testimony whereof, we have hereunto subscribed our names this 8th day of August, 1922.

OTTO H. ESCHHOLZ.
CHARLES F. WAGNER.
